UNITED STATES PATENT OFFICE.

EDMUND H. JONES, OF MILWAUKEE, WISCONSIN, ASSIGNOR TO MILWAUKEE CORRUGATING COMPANY, OF MILWAUKEE, WISCONSIN, A CORPORATION OF WISCONSIN.

CORNER BEAD.

Application filed April 28, 1927. Serial No. 187,139.

This invention relates in general to plaster terminals or bases such as corner beads or the like. One object of the invention is to provide a device of this character embodying wings of expanded metal and so constructed and organized as to cushion and relieve the wings of the expanded metal and their strands of shocks and strains which tend to break or snap the strands. Another object is to provide a device of this character which possesses not only features of general resiliency but which is also adapted to interlock in a positive and effective manner with the plastic coating and which is of simple and durable construction, reliable and effective in operation and easy and comparatively inexpensive to manufacture. Other objects and advantages reside in certain novel features of the construction, arrangement and combination of parts which will be hereinafter more fully described and particularly pointed out in the appended claim, reference being had to the accompanying drawings forming a part of this specification, and in which:

Figure 1 is a fragmentary perspective view showing the plaster base or terminal embodying the present invention, and

Figure 2 is a view thereof in horizontal section.

Referring to the drawing, wherein for the sake of illustration is shown one embodiment of the invention the numeral 1 designates a broad rounded body plate of imperforated or unexpanded sheet metal. Diverging wings 2 of expanded metal are also provided and are formed along the outer edges of the connecting portions 3, the connecting portions being in turn integral with the edges of the body plate 1.

As shown in Figure 2, the body plate 1 may be of substantially arcuate form in cross section. From each edge of this body portion an inturned section 4 of the connecting portion 3 extends, the section 4 being bent back under the body plate and lying in close proximity thereto, although being slightly spaced therefrom. Beyond the inturned section 4 the connecting portion has reversely bent or outwardly curving sections 5, and it is from these sections 5 of the connecting

portions that the wings 2 extend. It is to be noted that the sections of the connecting portions are not only spaced from the body plate 55 1, but are also spaced from each other. The connecting portions 5 are of unexpanded metal and thus may be bent or flexed as shown in the drawings. Moreover, due to 60 their formation and to the clearance between them and the body plate afforded by their spacing, they yield or flex to cushion and absorb shocks and strains to which the wings 2 are subjected. In other words, should 65 either wing 2 be subjected to bending or distorting pressure or shock, it will not be distorted and its strands will not be cracked or broken because the connecting portions can and will flex to relieve the pressure or 70 stress and prevent injury to the strands or meshes of the expanded metal.

The device not only has these advantages, but by virtue of the reverse bending of the sections of the connecting portion pockets P 75 are defined which adapt the device to interlock positively and effectively with the plastic coatings C designated by the dash lines in Figure 2.

From the foregoing it will be seen that a 80 plaster base or terminal is provided which may be easily constructed from a single piece of metal which can and does embody a broad and curved nose or body plate and which utilizes wings of expanded metal in such a 85 novel and effective manner as to impart to the plaster base or terminal extremely desirable shock absorbing and cushioning features. It is to be noted in this connection that the expanded wings are not only relieved of cracking or distorting strains by 90 the resiliency of the connecting portions, but also that the body plate or nose can take shocks, breaks or strains without distortion due to the resilient support afforded by the 95 cushioning and connecting portions. In addition to these advantages there is the further advantage of the positive interlock which the base or terminal provides between 100 itself and the plaster.

In general, the plaster terminal or base is of simple and durable construction and has all the advantages of a broad body plate and all of the advantages of expanded metal wings in addition to the special advantages 105 enumerated. The connecting portions as

well as the body plate, are imperforate metal, and thus are well able to stand the usage to which they are subjected.

The invention claimed is:

- 5 A device of the character described comprising a broad rounded body plate of substantially arcuate form in cross section and constituted of imperforate metal, diverging wings of expanded metal, and connecting
- 10 portions of unexpanded metal integral with the wings and with the body plate, each connecting portion including an inturned section extending from one margin of the body plate beneath the body plate and positioned close up against the under-face of the
- 15

body plate although just slightly spaced therefrom, each connecting portion also including a reversely bent and curved section between the inturned section and the associated wing, the connecting portions being 20 spaced from each other whereby clearance is afforded to permit the connecting portions to flex and take up shocks and strains, said connecting portions defining pockets 25 adapted to interlock with the plaster, said pockets terminating at the exposed edges of the body plate.

In witness whereof, I hereto affix my signature.

EDMUND H. JONES.
